UNITED STATES PATENT OFFICE.

GEORGE W. CARPENTER, OF TOLEDO, OHIO.

SHAFT-SUPPORT FOR VEHICLES.

SPECIFICATION forming part of Letters Patent No. 630,654, dated August 8, 1899.

Application filed May 18, 1899. Serial No. 717,283. (No model.)

To all whom it may concern:

Be it known that I, GEORGE W. CARPENTER, a citizen of the United States, residing at Toledo, in the county of Lucas and State of Ohio, have invented new and useful Improvements in Shaft-Supports for Vehicles, of which the following is a specification.

My invention relates to shaft-supports for vehicles by which the shafts may be supported and the weight of the same to a great extent taken off the horse or other draft-animal. It will also effectually prevent rattling of the thill-coupling.

The object of the invention is to provide an improved construction of the same which shall possess superior advantages with respect to efficiency in use.

The invention consists in the novel construction and combination of parts hereinafter fully described and claimed.

In the accompanying drawings, Figure 1 is a perspective view of the spring which supports the shafts. Fig. 2 is a transverse section of a vehicle-axle, showing the shaft-support connected therewith.

In the said drawings the reference numeral 1 designates a vehicle-axle, and 2 the clip, provided with a lug 3, to which the thill 4 is pivoted. The numeral 4^a designates the plate located below the clip, and 5 the nuts which are screwed on the ends of the bolts 6, passing through said plate, by which the clip is secured to the axle. The numeral 7 designates one of the shafts connected with the thill. All of these parts may be of any ordinary or suitable construction and form no part of the present invention.

The numeral 8 designates the thill and shaft support, consisting of a single piece of stiff spring-wire bent over near the center, forming an upwardly-extending loop 9, which when the support is connected with the axle bears against the rear side of the clip. Said wire is then bent into two series of coils 10, at right angles to said loop, which also abut against the rear of the clip. The wire is then curved upwardly, forming two arms 12, which

extend past the thill and one of which has its end bent inwardly at a right angle, forming an arm 13. The extremities of the wire are then bent at an angle to each other, forming interlocking hooks 15. Passing around the plate at the lower end of the clip is a holder 16, of spring wire, comprising the central portion 17 and parallel rearwardly-extending arms 18, the ends of which are bent outwardly and engage with the said coils, and thus hold the support in place.

The operation of the invention will be readily understood, and when the spring-support is connected with the clip by means of the holder 16 and the hooked upper ends interlocked in front of the thill the latter and the shaft will be supported under spring-tension, so that while the horse is relieved of a greater part of the weight of the shafts and thills they will give or yield when the vehicle is passing over rough or uneven roads. By the invention also rattling of the thills is prevented.

Having thus fully described my invention, what I claim is—

In a thill-coupling, the combination with the axle, the clip and the thill, of the spring-support comprising a single piece of wire bent to form a loop bearing against the rear of the clip, the spring-coils also bearing against said clip, the curved arms, one of which is bent at a right angle and the ends of said arms formed with interlocking hooks, and the loop consisting of a single piece of wire bent to form transverse and longitudinal arms and bearing against the lower end of the loop, and having the ends bent outwardly at right angles and engaging with said coils, substantially as described.

In testimony whereof I have hereunto set my hand in presence of two subscribing witnesses.

GEORGE W. CARPENTER.
